SIGNAL-CONTROLLED PRINTING APPARATUS

Henry L. Tholstrup, Rochester, N. Y., assignor to
International Business Machines Corporation,
New York, N. Y., a corporation of New York

Application April 19, 1945, Serial No. 589,112

3 Claims. (Cl. 197-20)

1

This invention relates generally to signal-controlled printing apparatus such, for example, as a typewriter which is automatically operated under the control of data-representing designations which have been previously recorded in a record sheet, or tape, according to a predetermined code system; the present application being a continuation in part of my copending Patent No. 2,378,371, granted June 12, 1945, on application, Serial No. 492,896, filed June 30, 1943.

While the signal-controlled printing apparatus of the present invention may be constructed in a variety of ways, it will be noted that the embodiment disclosed herein is the same in many respects as that disclosed in my said copending patent. As will appear more fully hereinafter, the disclosed embodiment comprises generally a tape reader, an electrical translator, and a typewriter. The reader operates cyclically and during each cycle senses a code designation in the record tape and as a part of the sensing operation produces a signal signifying the designation sensed. The electrical translator is adjusted in response to the sensing of each code designation to provide a circuit flow path corresponding to each such sensed code designation and to the signal produced thereby. The typewriter comprises the usual type bars carrying character type elements of different case or class, a platen for holding the copy sheet on which the data is to be printed, and a case shifting mechanism providing relative adjustment between the platen and type bars so as to print from the different case type. The typewriter also comprises an electrically responsive actuator for effecting a printing operation of each of the type bars and an electrically responsive actuator for effecting each of the functional operations of the typewriter, such as case shift, shift release, space, back space, tabulating and carriage return. When a record tape is prepared, code designations representing these functional operations are recorded therein along with the character code designations. When a code designation is sensed and the circuit flow path corresponding thereto is established by the translator, the closing of the circuit including such path energizes the related actuator to operate the typewriter in accordance with the designation sensed; i. e., if the designation sensed represents a character, the typewriter will print such character, or, if the sensed designation represents a functional operation, such operation will be effected.

It is a general object of the present invention to provide a signal-controlled printing apparatus

which is of improved construction and arrangement of parts and which includes as one feature thereof a provision for automatically stopping the operation of the apparatus in response to the producing of a significant code signal.

A further and more specific object of the present invention is to provide a new and improved signal-controlled printing apparatus which, when a certain code signal is produced with the typewriter in its normal adjusted case position, will cause the printing of a character corresponding to such code signal, and which, when the same code signal is produced with the typewriter adjusted to its shifted case position, will prevent further producing of code signals and will thereby stop the operation of the apparatus.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a plan view showing generally the units composing one preferred embodiment of the present invention;

Fig. 2 is an enlarged fragmentary plan sectional view showing in detail the mechanical working parts of the reader, which forms a component part of the preferred embodiment shown in Fig. 1; certain of the parts being broken away to illustrate the details of construction more completely;

Fig. 3 is a fragmentary vertical sectional view taken on the line 3-3 of Fig. 2;

Fig. 4 is a fragmentary vertical sectional view taken on the line 4-4 of Fig. 2, and illustrating the tape feeding mechanism;

Fig. 5 is a fragmentary vertical section through the reader, the section being taken at right angles to Figs. 3 and 4 and being indicated by the line 5-5 of Fig. 2;

Fig. 6 is a fragmentary vertical sectional view taken on the line 6-6 of Fig. 2, and illustrating the clutch mechanism and its controlling magnet which function to connect the reader operating shaft with a source of power;

Fig. 7 is a fragmentary vertical section taken on the line 7-7 of Fig. 3 and showing the code sensing pins of the reader and the manner in which each pin controls its related sensing contacts;

Fig. 8 is a transverse vertical sectional view through the center of the typewriter, the section being taken on the line 8-8 of Fig. 1;

Fig. 9 is a fragmentary vertical sectional

view through the typewriter in a plane parallel to and spaced from the plane of Fig. 8, and illustrating the mechanism for effecting case shift-
ing operations;

Fig. 10 is a fragmentary plan view of elements of the typewriter keyboard and showing the case shift and shift-release keys and the manner in which they are operated;

Fig. 11 is a fragmentary vertical sectional view showing the shift-lock key, the section being taken on the line 11—11 of Fig. 9;

Figs. 12a and 12b are two parts of an electrical wiring diagram illustrating diagrammatically the various control instrumentalities of the apparatus and the circuit wires connecting them; and

Fig. 13 is a view showing a portion of a record tape bearing all of the code hole designations of a pre-selected combinational hole code system.

Before considering in detail the construction and operation of the illustrated embodiment of the invention, it will be helpful to consider first one practical example of a pre-selected combinational code by means of which intelligence, such for example, as a letter which it is desired to transcribe, can be recorded on a record strip or tape. In Fig. 13, a portion of a record tape 10 is shown, and punched in the tape are all of the code hole designations of a combinational six-hole code. The six code positions are indicated at both ends of the tape 10 by the reference numerals 1 to 6, inclusive. Each code designation is arranged in a vertical column or recording field, and opposite the several fields bearing the code designations and below the lower edge of the tape, are placed legends indicating, respectively, the characters or functional operations represented by the code designations in the fields. From a study of Fig. 13, it will be noted that most of the character code designations are indicated as representing two different characters, the character legends appearing therein in two transverse parallel rows extending lengthwise of the tape. The reason for the latter is that in the code system illustrated the "Shift" and "Release" code designations are used in conjunction with the character code designations to represent the different characters. The legends in the bottom transverse row may be properly referred to as "normal" or "letters" case characters and those in the upper row adjacent the lower edge of the tape as "shifted" or "figures" case characters. As will appear more fully hereinafter, the sensing of the "Shift" designation adjusts the typewriter to its shifted case position and, with one exception hereinafter explained, the subsequent sensing of the character code designations in the tape will result in the printing of the corresponding "shifted" case characters. Also, the sensing of the "Release" designation adjusts the typewriter to its normal case position and the subsequent sensing of the character code designations will result in the printing of the corresponding "normal" case characters.

The exception just noted is that with the typewriter in its shifted case position and upon the subsequent sensing of the designation having a code hole in the number 3 and number 5 code positions, the operation of the apparatus will be stopped, and with the typewriter in normal case position, the sensing of the same 3—5 code designation will print the letter character "H." The latter is an important feature of the present invention and will be explained more fully hereinafter. Also, the sensing of the 1—4—5—6 designa-

tion indicated by the legend "Stop" will provide for stopping the operation of the apparatus in a new and improved manner. It is noted that the sensing of any of the designations representing the typewriter operating functions, or that the sensing of the 1—4—5—6 designation indicated by the legend "Stop," will result in effecting the corresponding operation with the typewriter in either of its adjusted case positions.

10 In Fig. 13, the smaller holes 11 at the center of the tape 10 and within each of the several recording fields are for the purpose of feeding the tape lengthwise during the reading or sensing operation. The code hole designations and the feed holes 11 may be punched in the tape by any suitable form of code perforator (not shown herein).

Referring now in detail to the construction of the preferred embodiment disclosed in the drawings, it will be noted that the signal-controlled printing apparatus is shown in Fig. 1 as comprising generally a tape reader 100 enclosed within a suitable housing 12, and a power operated typewriter 200. As will appear more fully hereinafter, the apparatus also includes an electrical relay translator of the pyramid type, and certain mechanisms, devices, circuits, and other control instrumentalities which provide for the automatic operation of the typewriter under control of the code designations in the record tape 10 sensed by the reader. The translator and these other control devices, instrumentalities, etc., and their connecting circuit wires are shown diagrammatically in Figs. 12a and 12b. As will appear more fully hereinafter, these control instrumentalities are suitably mounted within the reader housing 12 and on and under the typewriter 200. The circuit wires connecting the control instrumentalities mounted in the reader 100 with those mounted on the typewriter 200 are suitably enclosed 40 within a cable RT shown in Fig. 1.

As viewed in Fig. 1 the reader is provided across its lower side with a platform or tape table 13 across which the record tape 10 bearing the recorded intelligence is fed step-by-step during the operation of the apparatus. A tape supply spool 15 is suitably mounted at the right-hand side of the table 13 and serves to support the record tape 10 to be read and transcribed. A second or tape storage spool 16 is provided at the left of the table 13; and, as will later appear, is rotated by a flexible belt 17 during operation of the apparatus, for the purpose of winding the tape thereon after it leaves the sensing station of the reader. The sensing station is indicated at 20 and, as will appear more fully hereinafter, the recording fields of the tape are successively sensed during successive operating cycles, by sensing elements located at the station 20. A removable gate 21 is provided at the sensing station for properly positioning and holding the tape with respect to the sensing elements. The tape 10 is guided in its movement toward the sensing station by a suitable guide member 22 fixed to the top of the tape table 13.

65 At the right-hand side of the reader 100 as viewed in Fig. 1, are provided three electrical switches indicated, respectively, at 24, 25, and 26. As will appear more fully hereinafter, the switch 24 is the power switch and when closed, connects a convenient source of alternating current with a motor for driving the reader unit and with a motor for operating the typewriter. The reader motor is indicated by the character RM in Figs. 2 and 12a, and the typewriter motor 70 by TM in Fig. 12b. The switch 25 is the start 75

switch and when closed, starts the sensing and feeding of the tape and the automatically controlled operation of the typewriter key members. The switch 26 is the stop switch and when closed instantly stops the feeding and sensing of the tape and the controlled operation of the typewriter.

The typewriter 200 which is shown in plan in Fig. 1 and the detail construction thereof in Figs. 8 to 11, inclusive, will be recognized as being a well known commercial form of power-driven typewriter and will be described more fully hereinafter. In Fig. 1, the typewriter 200 is shown as comprising a keyboard 210 including the required complement of character keys 211 which operate corresponding type bars 212, and the functional keys which include the shift key 213, shift lock key 214, shift release key, 215, the carriage return key 216, the back space key 217, and the tabulating key 218. The space bar is indicated at 223. The typewriter 200 also comprises the conventional rotatable platen 219 mounted on the typewriter carriage 220 and which supports a copy sheet indicated at 221 and on which the data recorded in the tape 10 is automatically typed.

At the lower and left-hand side of the typewriter as viewed in Fig. 1, is provided a power switch 224 which, when closed, like the power switch 24, connects a source of alternating current with the typewriter and reader motors. At the lower and right-hand side of the typewriter is mounted a start switch 225 and a stop switch 226 which function, respectively, the same as the switches 25 and 26 on the reader 100. Thus, the operation of the apparatus may be controlled from either the typewriter or from the reader. An insert switch 227 is also provided on the typewriter which, when open, prevents starting of the tape feeding and sensing mechanisms in the reader 100 and thereby eliminates control by the latter of the typewriter, so that the keys of the typewriter keyboard 210 can be operated manually without interference from the reader. The insert switch 227 will normally be closed, and will be opened when it is desired to type manually an insert in the data being transcribed; for example, when it is desired to type manually the name and address of the person to whom the transcribed copy is to be sent or any other data which will be of interest only to the recipient of the copy.

The detail construction of the reader is shown in Figs. 2 to 7, inclusive. The reader comprises the reader motor RM which is suitably mounted within the housing 12 and which operates continuously as long as either the power switch 24 or power switch 224 is closed. The motor is at all times operatively connected by a suitable flexible drive belt 30 with a power shaft 31, the latter being mounted for rotation within suitable bearings 32 mounted within a frame 33 which is bolted to the base 34 of the reader.

The reader 100 also comprises an operating shaft 35 which is aligned with the power shaft 31 and is supported for rotation within suitable bearings 36 carried by the reader frame 33. The shaft 35 will be referred to hereinafter as the "reader" shaft. A clutch 37, under the control of a clutch magnet CM, is operable to connect and disconnect the reader shaft 35 and the power shaft 31. The reader shaft effects the operation of the tape feeding and sensing means.

A cycle of operation of the apparatus is effected during each revolution of the shaft 35;

viz., the tape 10 is fed or spaced a distance sufficient to bring the next recording field of the tape into sensing position, such next field is sensed to determine the code designations therein, if any, and the typewriter is operated in response to the sensing of the code designation. As long as the shafts 31 and 35 are clutched together the cycles of operation are repeated and the typewriter continues to transcribe the data recorded in the tape being read.

In so far as the present invention is concerned, any suitable form of clutch may be used to connect the reader shaft 35 to the continuously operated power shaft. The clutch 37 which is shown, is well known to those skilled in this art, it being substantially the same as that disclosed in the U. S. Patent No. 2,206,646, granted July 2, 1940. If desired, reference may be had to said patent for a complete showing of the structural details thereof. For the purposes of the present disclosure, it is believed sufficient to say that the clutch comprises a driving element in the form of a toothed wheel 40 fixed to the end of the power shaft 31, and a driven element in the form of a barrel 41 fixed to the reader shaft 35 and carrying a radially slidable clutch pawl 42. The barrel 41 is formed with a diametrically disposed slot 43 within which the pawl 42 is slidably mounted. To the outer end of the pawl 42 is fixed a tooth element 44 which, when the pawl 42 is moved radially inward, engages the toothed wheel 40 to provide the driving connection between the shafts 31 and 35. The pawl 42 is biased in a clutch engaging direction by a suitable spring mounted within the clutch barrel 41. A clutch releasing lever 45 also extends diametrically across the clutch barrel and at right angles to the slot 43 and is mounted for limited angular movement therein. The lever is provided with an outer extension 46 which, when intercepted and engaged by the outer end of one arm 47 of a rocking lever 48, is moved to move the clutch pawl 42 radially outward against the force of the aforementioned spring in the barrel 41 to disengage the clutch.

The clutch parts are shown in Figs. 2, 5, and 6 in their declutched position which is the home or starting position of the reader. The rocking lever 48 is mounted on a stud 50 carried by a part of the frame 33 and includes a second arm 51 which carries at its outer end the armature 52 of the clutch magnet CM. When the clutch magnet CM is energized, the lever 48 is rocked counterclockwise, as viewed in Fig. 6, which moves the outer end of the arm 47 upward and thereby releases the outer extension 46 of the releasing lever 45, and the clutch spring within the clutch barrel 41 then moves the pawl 42 radially inward to engage the toothed wheel 40 in the manner explained above. When the clutch magnet CM is deenergized, a tension spring 53 rocks the lever 48 clockwise and moves the outer end of the arm 47 into the path of the outer extension 46 of the lever so that the latter is engaged and moved to move the pawl outward to disengage the clutch.

In order to prevent rebound of the parts when the clutch is disengaged and in order to hold the reader shaft 35 in the home position, the clutch barrel 41 is also provided with an annular extension or collar 54 having a notch 55 formed therein which, when the clutch is disengaged, receives the outer end of an arm 56 of a detent lever 57. The detent lever 57 is also pivoted on the stud 50 and includes another arm 58 which

is connected to the armature 52 by means of the tension spring 53 previously mentioned. Thus, the spring 53 serves the dual purpose of urging the arm 56 into engagement with the periphery of the collar 54 so that it will fit within the notch 55 in home position, and to urge the arm 47 into position to intercept the extension 46 of the pawl releasing lever 45 and thereby declutch the parts.

As stated above, during the first part of each revolution of the reader shaft 35, the tape is fed on spaced lengthwise to bring a new recording field into sensing position. The tape feeding mechanism is shown more clearly in Figs. 2 and 4, and comprises a cam 60 mounted on the reader shaft 35 and cooperating with a rocking lever 61 pivoted on a fixed stud 62 carried by the frame 33 and comprising a pair of arms 63 and 64. The cam 60 and lever 61 are shown in Fig. 4 in the starting or home position and are so constructed that when the cam 60 begins to rotate in a counterclockwise direction, it first engages the arm 63 to rock the lever 61 counterclockwise and then engages the other arm 64 to rock the lever 61 clockwise and return the same to the position shown. A link 66 is pivoted at its lower end to the outer end of arm 64 and extends upwardly therefrom and is pivoted at its upper end by a stud 67 to a second link 68. The link 68 is also pivoted to a shaft 70 and serves to hold the link 66 in its upright position shown.

Also pivotally connected on the stud 67 is a feed pawl 71 which is held in operative engagement with a ratchet wheel 72 fixed to the shaft 70, by means of a tension spring 73 connecting outer extending arms of the pawl 71 and the link 68. A detent 74 is pivotally supported by a fixed stud 75 and is held in engagement with the teeth of the ratchet wheel 72 by means of a tension spring 76 and thereby serves to prevent reverse movement of the ratchet wheel 72 and shaft 70. From the above, it is apparent that when the clutch 37 is engaged to rotate the reader shaft 35 and when the lever 61 is first rocked counterclockwise by the cam 60, the pawl 71 will be moved downwardly thereby and will rotate the ratchet 72 and shaft 70 counterclockwise; and, when the cam 60 rocks the lever 61 clockwise, the pawl 71 will be moved upward to engage the next tooth of the ratchet 72.

The shaft 70 is the tape feed shaft and is provided with a feed wheel 77 having radially extending pins 78 which are adapted to engage the feed holes 11 in the tape 10. Thus, when the feed shaft is partially rotated in the manner just described, the tape is fed to the left as viewed in Figs. 1 and 2, a distance equal to the width of a recording field. The belt 17 which rotates the spool 16 shown in Fig. 1, is driven from a pulley 79 fixed to the tape feed shaft 70.

The mechanism for successively sensing the recording fields of the tape comprises six sensing pins indicated, respectively, by the characters S1 to S6, inclusive. There is one pin for each of the code hole positions and the pins are arranged in a single vertical plane extending at right angles to the direction of movement of the tape, and so that when the tape comes to rest at the end of a feeding operation, the upper end of each pin will be directly beneath its corresponding code hole position in the field of the tape, then in position to be sensed. The pins are guided for vertical movement within aligned openings in spaced guide blocks 80 and 81, respectively, which are suitably fixed to the frame

5 33. Aligned pairs of guide openings are also provided in the table 43 and in the gate 24 and they are aligned with corresponding openings in the guide blocks so that during a sensing operation each pin can be moved upward and through the tape when there is a hole in the code position in the tape corresponding to such pin.

10 The six sensing pins are supported and operatively connected, respectively, at their lower ends to six pairs of spring blade contacts indicated, respectively, by the characters C1 to C6, inclusive. Each pair of the contacts comprises an upper fixed blade 82 and a lower movable spring blade 83 which extends outwardly beyond the end of its related fixed blade and is connected at its outer end to the lower end of its related sensing pin. The construction is such that the spring blades 83 constantly urge their respective contacts upward into closed position and their related sensing pins upward as viewed in Figs. 3 and 7. Between sensing operations, the six sensing pins are held in home position, the position shown in Fig. 3, by the outer lateral edge 84 of 15 a vane 85, which edge extends across all of the pins and within transversely aligned notches 86 provided, respectively, in the sides of the pins. The vane 85 is, in effect, a rocker arm pivotally supported on a rod 87 carried by the frame 33 and constantly urged to move in a clockwise direction, as viewed in Fig. 3, by a tension spring 88. The vane 85 is provided at its center with a depending arm 89 which carries at its lower end a roller 90 held by the spring 88 in contact with the face of a cam 91 mounted on the reader shaft 35. When the roller 90 is in engagement with the high point of the cam 91, the vane 85 is held in the position shown in Fig. 3 where the several sensing pins are held in their respective lower positions and the pairs of contacts controlled thereby are held open.

20 After the tape has been spaced by the feeding mechanism in the manner previously described and has come to rest with the new recording field above the sensing pins, the shaft 35 and cam 91 will have rotated counterclockwise from the position shown in Fig. 3, 94° of a revolution. When the shaft 35 has rotated 114°, the roller 90 will begin to move inwardly from the high point of the cam 91, and the vane 85 will move in a clockwise direction due to the force of the spring 88. The sensing pins S1 to S6, inclusive, will also follow the end 84 of the vane 85 upward due to the spring force in their respective movable blades 83. If there be a hole in the code position of the tape immediately above a sensing pin, its movable spring blade 83 will continue to move the pin upward and through such code hole and to a point where the pair of contacts controlled thereby will close. If there be no code hole in the position above a sensing pin, the upper end of such pin will strike the tape 10 and will be held thereby against further upward movement, and in the latter position its related pair of contacts are held open.

25 By way of example, Fig. 7 shows the relative position of the parts during the sensing of a record field bearing the 1-3-5 code designation, which as shown in Fig. 13 represents the normal case letter character "Y" and the shifter case figure character "6." Sensing pins S1, S3, and S5 are shown as having passed through code holes in the corresponding code positions 1, 3, and 5 in the tape 10 and their related contacts C1, C3, and C5 are shown closed. The sensing pins S2, S4,

and S_6 have been stopped in their upward movement by the tape and their related contacts C_2 , C_4 , and C_6 are thereby held open.

From the foregoing, it is apparent that during a sensing or reading operation the contacts C_1 to C_6 , inclusive, are closed by their related sensing pins singly or in combination, depending upon the code hole designation in the record field of the tape being sensed. The sensing operation is terminated by the high point of the cam 91 engaging the roller 90 on the arm 89 and moving the vane 85 counterclockwise, as viewed in Fig. 3, so that the end 84 thereof engages again the lower ends of the notches 86 in the several sensing pins S_1 to S_6 inclusive, and thereby moves the latter downward to the position shown in Fig. 3, where the related contacts are held in open position. The sensing operation is completed and the vane 85 is restored to home position at approximately 346° of each revolution.

In order to provide for automatically stopping the reading or sensing operation when there is no tape at the sensing station, a seventh pin 94 is mounted for vertical sliding movement within aligned openings in the spaced guide blocks 80 and 81 and in the table 13 and the gate 21 and is positioned so that it will engage the central portions of the tape. The lower end of the pin 94 is supported and operatively connected to the movable spring blade 95 carrying one of a pair of contacts 96 . The blade 95 is normally urged upward by the spring force inherent therein, to open the contacts 96 and move the pin 94 upward. If there is a tape at the sensing station 20 , the upper end of the pin 94 engages the underside of the tape and the contacts 96 are held closed. This is the position of the parts shown in Fig. 7. When the tape runs out, the pin 94 moves upward and opens the contacts 96 which, as will later appear, opens the energizing circuit for the clutch magnet CM and thereby stops the feeding and sensing operation of the reader. In Fig. 3, no tape is shown at the sensing position 20 and the pin 94 is shown in the upper position where the contacts 96 are open. The pin 94 is made sufficiently large in diameter so that the feed holes 11 in the tape 10 will not affect its operation.

Each sensing or reading operation produces a significant signal corresponding to the designation sensed. As will be explained more fully hereinafter in connection with the description of the wiring diagram shown in Figs. 12a and 12b, the sensing contacts C_1 to C_6 , inclusive, control, respectively, the flow of direct current within six signal circuits, the latter including, respectively, six translator relays M_1 to M_6 , inclusive, of a relay type of translator mechanism which, as stated, is diagrammatically shown in Fig. 12a. At this point, it is sufficient to say that by energizing translator relays M_1 to M_6 , inclusive, singly and in combination, due to the selective closing of their related contacts C_1 to C_6 , inclusive, during the reading operation described above, a number of controlling circuit paths through the translator are selectively established, which circuit paths correspond, respectively, to the code designation sensed. With certain exceptions hereinafter explained, each of these circuit paths, when closed, actuates a related key member of the typewriter 200 .

A cam 102 is also fixed to the reader shaft 35 and controls through a pivoted follower 103 the operation of a pair of spring blade contacts 104 . As will appear more fully hereinafter the contacts

104 control the flow of signal current from a suitable D. C. source and through the contacts C_1 to C_6 inclusive, in parallel, to their related translator magnets M_1 to M_6 , inclusive. The contacts 104 may be termed the D. C. common contacts and are normally held open by their movable spring blade. The cam 102 is so shaped and positioned on the operating shaft 35 that the contacts 104 are closed at 142° of a revolution which is after the time for closing the sensing contacts C_1 to C_6 , inclusive, and are opened at 311° which is before the sensing contacts are opened by the vane 85 . The purpose of the D. C. common contacts is to provide for simultaneously energizing and deenergizing the translator relays M_1 to M_6 , inclusive.

A cam 106 is also fixed to the reader shaft 35 and controls through a pivoted follower 107 the operation of a pair of normally open spring blade contacts 108 which are herein termed the A. C. common contacts. As will appear more fully hereinafter, the current which flows through the controlling circuit paths of the translator previously mentioned as being conditioned by the selective energization of the translator relays M_1 to M_6 , inclusive, is A. C. current, and the cam 106 is so shaped that it connects the source of A. C. current with these circuit paths at a predetermined point in each cycle of operation. In the structure shown, the cam effects the closing of the A. C. common contacts 108 at approximately 170° of each revolution and opens the contacts at 294° .

The detail construction of the typewriter is shown in Figs. 8 to 11, inclusive, and as stated previously, is a well known commercial form of power driven typewriter. The structural features and principles of operation of this typewriter are fully disclosed in a number of U. S. patents, among which is Patent No. 1,777,055, granted September 30, 1930, which discloses the general principles of operation of the key levers and how they control through related cam units, the operation of the type bars. In view of the detailed description of the construction and operation of the parts given in the patent just mentioned, only a brief description will be given herein which will be sufficient to enable the present invention to be understood. Reference may be had to the aforementioned patent for further details.

As shown in Fig. 8, the character keys 211 are mounted, respectively, on key levers 228 , the latter being pivoted on a rod 229 which is supported by a cross frame 230 rigidly mounted in the typewriter frame. Rotatably mounted in the base 231 is the power roller 232 which is rotated in the direction of the arrow by means of an A. C. motor, not shown in Fig. 8, but indicated diagrammatically at TM in Fig. 12b. When the machine is in use, the power roller rotates continually.

Cooperating with the power roller 232 are the cam units 233 which are pivotally mounted on rods 234 extending parallel with the power roller 232 . There is a cam unit 233 associated with each of the key levers 228 , and each of the cam units which is operated by a character key 211 , is connected by a link 235 with a sub-lever 236 pivoted on rod 229 . The sub-levers 236 are connected by links 237 to type bars 212 through the medium of toggles 238 . The type bars 212 are pivoted in the usual type bar segment 239 and the latter is provided with a type guide 240 located in front of the platen 219 . As stated pre-

11

viously, the platen is adapted to support the work sheet 221 and is rotatably mounted in the carriage 220, and the latter is supported for lengthwise movement on front and rear rails 241 and 242, respectively, by means of suitable anti-friction roller trucks. Springs 243 connected to a curved spring anchoring member 244 and to toggles 238, provide means for locking the toggles in their normal or inactive position shown in Fig. 8.

When any character key 211 is manually depressed, its related cam unit 233 is caused to operatively engage the power roller 232 in a well known way, thereby rocking the cam unit 233 clockwise or counterclockwise, according to whether the operative cam unit is pivoted on the left hand or right hand rod 234, respectively, as viewed in Fig. 8. The rocking of the cam unit 233 causes its link 235 to be drawn downwardly, thereby rocking the corresponding sub-lever 236 in a clockwise direction. This movement of the sub-lever 236, through the corresponding link 237 and toggle 238, causes the type bar 212 associated with the selected key to rock in a counterclockwise direction to effect the impression of the type upon the work sheet 221 wrapped around the platen 219. The type bar, near the end of its operating stroke, engages the usual universal bar 245 and causes the universal bar to move rearwardly and downwardly in Fig. 8 to space the carriage forward in a manner not disclosed in detail herein, but which is well known to those skilled in the art.

To each of the character key levers 228 is connected by a spring 246, an electrically responsive actuator in the form of a solenoid 247 which, when energized, pulls its related key lever 228 downward to operate the related cam unit 233 and type bar 212 in the same manner as described above when the related key 211 is manually depressed. As will appear more fully hereinafter, the solenoids 247 are selectively energized by the A. C. controlling circuit flow paths previously mentioned as being selectively established by the energizing of the translator relays M1 to M6, inclusive.

As will be readily understood by those skilled in the typewriter art, one of the cam units 233 is operated by manually depressing the space bar 223 and its related key lever, and such cam unit when operated effects the rearward movement of the universal bar 245 to space the carriage. The detail mechanism for effecting this operation has not been shown herein as it would be a needless duplication of drawing and description. A solenoid 247 is also provided for operating the key lever on which the space bar 223 is mounted. The latter solenoid is shown diagrammatically in Fig. 12b.

The type bar segment 239 is mounted in a frame 249 and both the segment and the frame form parts of the type basket. The type basket is movably mounted in the framework of the machine for case shifting movement in a well known way and normally occupies an elevated position shown in Figs. 8 and 9 for the typing of the normal case characters referred to hereinabove. In Figs. 1 and 8 only one of the type bars 212 has been shown. The normal case type element on the bar 212 is indicated at 212a and the shifted case type element at 212b. The case shifting mechanism for drawing the type basket downward to permit the printing of shifted case characters is described in U. S. Patent No. 75

12

1,945,097, granted January 30, 1934, and is partly shown in Fig. 9 hereof.

Secured, respectively, to the back of the type basket frame 249 and on opposite sides thereof, 5 are two brackets 250. The brackets 250 are connected by links 251 to the outer ends of lever arms 252, the latter being fixed respectively, on the ends of a transverse shaft 253 journaled in the framework of the machine. Pivoted on a stud 254 at one side of the machine is a lever 255 having two pins 256 and 257, engageable by the short arms of a T-shaped lever 258, the latter being pivotally mounted at 248 on one arm 259 of a three-armed lever 260. The lever 255 is connected by a link 261 to the outer portions of one 15 of the lever arms 252 and at points spaced from the connection of such arm and its link 251. The T-lever 258 has a stud 262 projecting into a slot 20 formed in the rear end of an arm 263 comprising a rearward extension of the left-hand shift key lever 264 as viewed in Figs. 1 and 10. One arm 25 of lever 260 is connected by a link 265 to a cam unit 266 which is controlled by the shift key lever 264 in substantially the same manner as cam units 233 are controlled by the key levers 228, described above.

The type basket is manually shifted downward to shifted case position when the shift key 213 is mounted on key lever 264 is depressed and is 30 returned to normal case position when the key 213 is released and moves upward. The key lever 264 is, therefore, held in its lower position while writing shifted case characters.

When the shift key lever 264 is depressed, the 35 T-lever 258 is elevated to bring the upper of the short arms thereof to a position behind or to the left of the pin 256, this movement taking place before the cam unit 266 controlled by the key lever 264 is operatively connected to the power roller 232. When the cam unit 266 is operated, the link 265 is drawn downwardly, thereby rocking lever 260 in a clockwise direction. This 40 draws the T-lever 258 to the right as viewed in Fig. 9, and thereby, through the engagement of said T-lever with the pin 256, rocks the lever 255 clockwise. Consequently, through the link connection 261, the lever arms 252 connected thereto and the transverse shaft 253 are rocked in a 45 counterclockwise direction, thereby pulling downward the links 251 which results in the type basket being drawn downward to shifted case position.

As disclosed fully in the aforementioned U. S. Patent No. 1,945,097, when the key lever 264 is 55 released so that it is returned upward to its normal case position by the spring 267, the cam unit 266 is again actuated by the power roller 232 so that the cam unit rocks in a counterclockwise direction, as before. When the key lever 264 is released and before the cam unit 266 is 60 actuated, the rearwardly extending arm 263 of the lever 264 moves downward and thereby permits the T-lever 258 to move downward and bring the lower of its short arms to a position behind or to the left of the lower pin 257. Consequently, when the cam unit 266 is rocked counterclockwise, as just stated, the cam unit through the link 265 rocks the lever 260 clockwise, and the latter through the T-lever 258 and pin 257, rocks the lever 255 counterclockwise. The lever 255, through the link 261, rocks the arms 252 and transverse shaft 253 clockwise to return, through the links 251, the type basket to the 65 normal case position shown in Figs. 8 and 9.

In accordance with the present invention, a

set of transfer contacts 201 are adjusted to close one circuit path when the type basket occupies its normal case position, and are adjusted to open such one circuit path and to close a different circuit path when the type basket is moved to its shifted case position. As shown in Fig. 8 the transfer contacts 201 are suitably supported by the frame of the typewriter and comprise an upper fixed blade or strap 202 carrying a contact point 203, a lower fixed blade 204 carrying a contact point 205, and a center movable spring blade or strap 206 carrying a contact 207. The blade 206 is biased to move upward to close points 207 and 203. However, when the type basket occupies its normal case position, as shown in Fig. 8, the lower outer end of an actuating arm 208 holds the center blade 206 downward against the inherent spring force of the blade to close the points 207 and 205. The arm 208 is fixed to the transverse shaft 253 and is provided with a contact actuating roller 209 which engages the center blade 206 as shown in Fig. 8, when the type basket is in the normal case position. When the type basket is adjusted to its shifted case position in the manner explained above, the shaft 253 and arm 208 are moved counterclockwise and out of contact with the blade 206 and the latter moves upward by its inherent spring force to close points 207 and 203 and disengage points 207 and 204. As will appear more fully herein-after, the transfer contacts 201 function as a part of the means for controlling the operation of the reader and typewriter.

During the controlled operation of the typewriter by the sensing mechanism and the translator relays, the key lever 214 is pulled downward to shift the type basket to shifted case position by the energizing of a solenoid 268 having an armature 269 pivotally connected to a latching lever 270 which is, in turn, connected at its upper end to the lever 264 by a stud 271 fixed within an opening in the key lever 264 and projecting into a slot 272 formed in the latching lever 270. As will presently appear, the key lever 264 is locked down when it is shifted by the solenoid 268, and the key lever 264 is released to return the type basket to normal case position by the energizing of a second solenoid 273 which pulls down the shift-release lever 274 at the right of the typewriter (see Fig. 10). The solenoid 268 is energized as a result of sensing the "Shift" code designation in the tape 10 and the solenoid 273 is energized as a result of sensing the "Release" code designation (see Fig. 13). When the typewriter is operated manually, the shift key 213 is depressed and released to adjust the type basket to its shifted and normal case positions. The manually operable shift lock key or button 214 cooperates with the key lever 264 and latching lever 270 to lock the key lever 264 down in its shifted case position when it is desired to type manually a substantial number of shifted case characters. When the key lever 264 is locked down, it may be manually released by depressing the shift-release key 215 and its associated key lever 274.

The shift latching lever 270 is arranged on one side of the key lever 264 and the shift-lock button 214 on the opposite side thereof. The shift-lock button 214 is provided with a vertical slot 275 also receiving the stud 271 projecting from the lever. A detent 276 is fixed to a stationary portion 277 of the typewriter frame and cooperates with the latching lever 270 in locking the

key lever 264 down in shifted position. With the parts in their normal case position, as shown in Figs. 9, 10, and 11, the detent 276 engages the lowermost inner surface of the lever 270. A tension spring 278 connects the latch lever 270 with the shift key lever 264 and serves to hold the lever 270 in this position, the stud 271 extending from the lever 264 occupying the lower part of the slot 272. The shift lock button 214 is provided with a pin 279 which extends over the latching lever 270 and engages the top of the latter. With the parts in normal case position, the lever 270 supports the button 214 through the pin 279 and the stud 271 also occupies the lower part of the slot 275 in the button 214. The button 214 is also provided with spaced tabs 280 and 281, engaging respectively the upper and lower sides of the key lever 264, which aid in holding the button 214 in an upright position.

When the solenoid 268 is energized, the latching lever 270 is pulled downward thereby until the top of the slot 272 engages the stud 271, after which the key lever 264 will also be pulled down to actuate the cam unit 266 to shift the type basket to shifted case. When the latter happens, the detent 276 will have cleared a ledge portion 282 on the lever 270 and the spring 278, in conjunction with the off-center pivotal connection between the armature 269 and lever 270, will move the lever 270 to the right or counterclockwise as viewed in Fig. 9, until the ledge 282 is under the fixed detent 276, thus locking the latch lever 270 and key lever 264 down in its shifted position.

When the button 214 is manually depressed, it also moves the latching lever 270 downward, through the pin 279, until the top of the slot 272 engages the stud 271 after which the lever 264 will be moved downward with the lever 270 a distance sufficient to actuate the cam unit 266. When the latter occurs, the detent will have cleared the ledge portion 282 and the spring 278 will move the lever 270 counterclockwise, until the ledge 282 is under the detent 276, thus manually locking the latch lever 270 and the key lever 264 down in shifted position.

As stated above, the key lever 264 is released to return to lower case position by energizing the solenoid 273 or by depressing the shift-release key 215. To this end, a bail lever 284 is provided which comprises a pair of end plates 285 and 286 connected by a bail rod 287. The bail lever 284 is mounted for pivotal movement by studs 288 and 289 extending outwardly from the plates 285 and 286, and journaled, respectively, within opposite sides of the typewriter frame. A stud 290 extends inwardly from the end plate 286 and within a notch 291 formed in a downwardly extending projection of key lever 214 on which the key 215 is mounted (see Fig. 8). A second stud 292 extends inwardly from the end plate 285 and over the outer end 293 of latching lever 270. Thus, when the lever 270 is moved down by the energizing of solenoid 273 or by manually depressing the key 215, the bail lever is rocked about its pivotal support and the stud 292 engages the end 293 of latching lever 270 and thereby rocks the latter downward and clockwise to move the ledge portion 282 out from under the detent 276 which unlatches the lever 270. When the lever 270 is thus released, the lever 264 is permitted to move up under the force of its spring 267 to the normal case position shown in Fig. 9.

The other functional operations of the typewriter disclosed, such as back space, tabulating, and carriage return, are effected in a manner

well known to those skilled in this art. Consequently, a detail disclosure herein of the mechanisms for effecting these operating functions is considered unnecessary. They are disclosed fully in my said copending patent, of which this application is a continuation in part, and in prior patents identified therein. For the purposes of disclosing the present invention, it is considered sufficient to state that each of the keys 217, 218, and 216 is mounted on a corresponding key lever similar to the levers 226 and 264, and when each key is depressed, it actuates a corresponding cam unit which in turn operates the mechanism for effecting the functional operation corresponding to the depressed key. Also, a solenoid 241 is connected to each of the key levers supporting the keys 217, 218, and 216 and when energized effects the operation of the corresponding cam unit in the same manner as when the keys are manually depressed.

Referring now to the wiring diagram shown in Figs. 12a and 12b, it is noted that all of the control instrumentalities and circuit wires located within the reader 100 are shown diagrammatically in Fig. 12a, and this includes the relay translator mechanism previously referred to herein, and that all of the control instrumentalities and circuit wires mounted on the typewriter are shown in Fig. 12b. For the purposes of simplicity, the circuit wires of the reader which are connected, respectively, by the individual wires within the cable RT (Fig. 1) with corresponding circuit wires in the typewriter are shown as terminating at the right-hand margin of Fig. 12a in plug socket connections, designated, respectively, as R1 to R56, inclusive. The corresponding circuit wires in the typewriter terminate at the left-hand margin of Fig. 12b in plug socket connections T1 to T56, inclusive. It is to be assumed that the plug sockets R1 to R56 are connected, respectively, to the plug sockets T1 to T56, inclusive, by the individual cable wires.

As stated above, the relay translator mechanism comprises the series of relays M1 to M6, inclusive, which, during each cycle of operation of the reader, are energized singly or in combination, as a result of the producing of significant signals by the sensing of code hole designations in the record tape. The relay translator shown is a well known mechanism which, in response to the selective energization of its relay magnets in the manner just stated, sets up a number of controlling circuit paths corresponding, respectively, to the code designations sensed. The relays M1 to M6, inclusive, control, respectively, the operation of one or more related transfer contacts which during each sensing cycle will be transferred, or left at normal position, so that the contacts may be connected in combinational series to condition the just mentioned controlling circuit paths. As shown, the armature of relay M1 operates a pair of contacts M1-1; the armature of relay M2 operates two pairs of contacts M2-1 and M2-2; the armature of relay M3 operates four pair of contacts M3-1 to M3-4, inclusive; the armature of relay M4 operates eight contacts M4-1 to M4-8, inclusive; the armature of relay M5 operates sixteen contacts M5-1 to M5-16, inclusive; and the armature of relay M6 operates thirty-two contacts M6-1 to M6-32, inclusive. In Fig. 12a, these various relay-controlled transfer contacts are shown in their upper or normal position, which is the position they occupy when their related operating relays are deenergized. When any

translator relay is energized, all of its related contacts transfer to the lower position.

With the exception of plug socket connection T8, the plug socket connections T1 to T48, inclusive, are shown in Fig. 12b as connected, respectively, by individual circuit wires with the solenoids 247, 268, and 273 which actuate the character and functional key levers of the typewriter previously described. Plug socket T8 is shown as connected to the center strap 206 of the transfer contacts 201, and the lower strap 204 is shown as connected to the solenoid 247 for the "H" key of the typewriter. The solenoids 247, 268, and 273 are shown in Fig. 12b in the same relative positions as their corresponding keys on the typewriter. Legends appear opposite the solenoids and indicate, respectively, the characters printed and the functional operations effected by the energizing of the solenoids. Where two character legends appear opposite a solenoid, the upper character is printed with the type basket in shifted case position and the lower character is printed with the type basket in normal case position. Where only one character legend is opposite a solenoid, such character is printed only when the type basket occupies its normal case position because the corresponding type bar carries only a normal case type element.

In Figs. 12a and 12b, all switches, solenoids, relays, contacts, and associated parts are shown in the positions they normally occupy with no tape under the sensing gate 21 (Fig. 1) and with both power switches 24 and 224 in open position and with the type basket in its normal case position shown in Fig. 8. A source of alternating current is indicated in Fig. 12a by the lead wires 400 and 401.

As stated previously, both the reader motor RM and the typewriter motor TM are operated when either the power switch 24 or the power switch 224 is in closed position. One side of the motor RM is permanently connected to the lead 400, and also one side of the motor TM is permanently connected to the lead 400 by a wire 402, plug socket connections R56 and T56, wire 403, and wire 404. Upon closing of switch 24, the other side of the motor RM is connected thereby to the other supply lead 401 by a wire 408, and the other side of the motor TM is connected to the supply lead 401 by a wire 405, plug socket connections T50 and R50 and wire 409. The closure of the switch 24 also energizes a rectifier transformer 406, one side of the primary being permanently connected to the supply lead 400, and the other side being connected to the wire 408, and through the latter and switch 24 with the other supply wire 401.

With one side of the motors RM and TM and transformer 406 being permanently connected to the lead 400 in the manner just explained, the closing of switch 224 also energizes the motors RM and TM and the transformer 406 as follows: from wire 401, wire 410, plug socket connections R55 and T55, wire 411, the switch 224, a wire 412, wire 413, and wire 405, to the other side of the motor TM; and through wire 405, plug socket connections T50 and R50, the wires 409 and 408, to the other side of the motor RM and the other side of the primary of transformer 406.

With the transformer 406 energized in the manner just explained, alternating current is supplied to the input terminals of a rectifier 415. The positive and negative DC output terminals of rectifier 415 are connected, respectively, to a plus bus 416 and to a minus bus 417. The opposite sides of the coil of a reader relay 420 are per-

manently connected with the plus bus 416 and the minus bus 417, so that as long as the rectifier is supplied with alternating current, the relay 420 remains energized. When the relay 420 is thus energized, the armature 423 thereof connects the minus bus 417 to each of wires 431, 432, 433, 434, 435, and 436, which are respectively connected to the return sides of the six translator relays M1 to M6, inclusive.

With a record tape 10 properly positioned under the gate 21 in the reader 100, the contacts 96 are closed by the pin 94 and the apparatus is ready for successively reading and transcribing the code designations in the tape onto the record sheet 221 in the typewriter 200. The tape sensing and feeding operation is started by depressing either the reader start switch 25 or the typewriter start switch 225. The reader start switch 25 is provided with two pairs of spring blade contacts 440 and 441, respectively, the contacts 440 being normally open and being closed upon depressing the start switch 25, and the contacts 441 being normally closed, and being opened when the start switch 25 is depressed. The movable one of the normally open contacts 440 is connected by a wire 442 with the plus bus 416. Thus, when contacts 440 are closed by depressing switch 25, direct current will flow from the plus bus 416 through the wire 442, contacts 440, a wire 443, plug socket connections R53 and T53, a wire 444, the normally closed insert switch 227, a wire 445, plug socket connections T51 and R51, a wire 446, normally closed pick-up contacts 447 of a master control relay 448, a wire 449 to one side of a main coil 450 of such relay 448; and, from the coil 450, through wire 451, the now closed contacts 96, and a wire 452 to the minus bus 417. When the master control relay 448 is thus energized, the armature thereof moves to the right and thereby opens the pick-up contacts 447 and closes a pair of holding contacts 453, the latter being connected directly to the plus bus 416 by a wire 454. The contacts 447 and 453 are of the overlapping type, that is, the holding contacts 453 make before the pick-up contacts 447 break. With the holding contacts 453 closed, direct current will flow through the holding circuit for the main coil 450 which is traced as follows: from the plus bus 416, through the wire 454, contacts 453, wire 449, to the coil 450; and, from the latter, through wire 451, contacts 96, and wire 452, to the minus bus 417.

Contacts 455 also close when master control relay 448 is energized and they thereby condition an energizing circuit for the clutch magnet CM. This conditioned clutch magnet control circuit is established when the start switch contacts 441 are again closed by the operator releasing the start switch 25. The clutch magnet circuit is traced as follows: from the positive bus 416 through the plug socket connections R54 and T54, a wire 456, normally closed contacts 373 which are under the control of elements for effecting carriage return of the typewriter, a wire 458, normally closed contacts 326 which are under the control of elements for effecting tabulating operations of the typewriter and will be explained hereinafter, a wire 459, normally closed contacts 460 of the typewriter start switch 225, wire 461, plug socket connections T52 and R52, wire 462, the now closed contacts 455 of the master control relay 448, a wire 463, the now closed contacts 441 of the start switch 25, wire 464, the clutch magnet CM, and from the latter through a wire 465, the now closed contacts 96,

and wire 452 to the minus bus 417. The clutch magnet circuit just traced directly controls the operation of the reader in the manner previously explained; i. e. when the clutch magnet CM is energized by the closing of this circuit, the operating shaft 35 of the reader is connected by the clutch 37 to the power shaft 31 and the successive cyclic tape feeding and sensing operations will begin and will continue at a rate determined by the designed speed of the power shaft until the clutch magnet CM is deenergized by the opening of any of the now closed contacts in its control circuit.

The typewriter start switch 225 is connected in parallel with the reader start switch 25, so that the operation of the apparatus may be started by depressing and releasing the switch 225 in the same manner as just described in connection with the switch 25. As shown, the switch 225 is provided with two pairs of spring blade contacts which are the normally closed contacts 460 mentioned above, and a normally open pair of contacts 467. One contact of the pair of contacts 467 is permanently connected to the DC plus bus 416 through the wire 456 and plug socket connections T54 and R54. The other contact of the pair of contacts 467 is connected by a wire 468 and a wire 469 with the normally closed insert switch 227 which, as explained previously in connection with switch 25, is connected to the DC minus bus 417 through the wire 445, plug socket connections T51 and R51, wire 446, pick-up contacts 447 of the master control relay 448, wire 449, coil 450, wire 451, contacts 96, and wire 452. Thus, with the apparatus at rest, by depressing the switch 225 to close its contacts 467, and open the contacts 460, a flow path for direct current is established through the pick-up contacts 447 and coil 450 of the master control relay 448, and the latter, when energized, will close its holding contacts 453 and remain energized by the holding circuit established thereby which was previously traced. As explained above, the contacts 455 are closed by the energizing of relay 448 and the clutch magnet circuit is conditioned thereby. When the start switch 225 is released, its contacts 460 again close and the conditioned energizing circuit for the clutch magnet CM is thereby established.

As described previously herein, when the reader shaft 35 commences to rotate, due to the energizing of the clutch magnet CM and the resulting engagement of clutch 37, the tape 10 is first spaced to move a record field into sensing position which is directly above the sensing pins S1 to S6, inclusive, and then the field is sensed by the pins to determine the code hole designation therein. As an example let it be assumed that the record field being sensed bears the code hole designation for the normal case letter character "Y" and the shifted case figure character "6," which, as shown in Fig. 13, comprises code holes in positions 1, 3, and 5. As shown in Fig. 7, and as previously explained, the sensing of the 1-3-5 code hole designation will result in the sensing pins S1, S3, and S5 moving upward through the code holes in the tape to close contacts C1, C3, and C5, respectively. The contacts C1, C3, and C5 will close at approximately 130° of the revolution of shaft 35 to condition signal circuits connected in parallel, and will remain closed until 325°, and the D. C. common contacts 104 are closed by the cam 102 at 142° to establish such signal circuits and are opened again at 311°. With the contacts C1, C3, and C5 closed, and with

the D. C. common contacts 104 closed, the signal current will flow from the D. C. positive bus 416 through cam contacts 104, the contacts C1, C3, and C5 in parallel, and through signal wires 471, 473, and 475 to translator relay magnets M1, M3, and M5, respectively, and from the latter through wires 431, 433, and 435, respectively, the closed contacts of reader relay 420, to the D. C. minus bus 417. With the translator relay magnets M1, M3, and M5 thus energized by the producing of a signal corresponding to the 1-3-5 code designation, their respective relay contacts are transferred to their lower positions. As the relays M2, M4, and M6 remain deenergized, their related transfer contacts will remain in their normal upper positions.

With the transfer contacts of the translator in the position just stated, and when the cam 105 on the reader shaft 35 closes the A. C. common contacts 108 at 170° of the revolution of shaft 35, alternating current will flow through the controlling circuit flow path established by the translator contacts, to the solenoid 247 controlling the key lever 228 for the normal case letter "Y" and shifted case numeral "6" on the typewriter, and thereby effect the operation of the related type bar 212 in the manner previously explained. Assuming the type basket to be in its normal case position, the energizing of the solenoid 247 as just explained will result in the normal case character "Y" being printed on the sheet 221. The closed A. C. circuit path for energizing the solenoid 247 is traceable as follows: from the A. C. supply lead 400, a wire 471, contacts 108 now closed, a wire 478, contacts M1-1 in the lower position, a wire 479, contacts M2-2 in the position shown, a wire 480, contacts M3-3 in the lower position, a wire 481, contacts M4-6 in the position shown, a wire 482, contacts M5-11 in the lower position, a wire 483, contacts M6-22 in the position shown, a wire 484, the plug socket connections R32 and T32, a wire 485, solenoid 247 for actuating the type bar carrying the normal case character "Y," a wire 486, and if the power switch 24 is closed, through the wires 413 and 405, plug socket connections T50 and R50, the wire 409, switch 24 to the A. C. supply wire 401. If instead, the switch 224 is closed, the circuit will include the wire 412, switch 224, wire 411, plug sockets T55 and R55, and wire 401.

From the foregoing it will be understood that if the clutch magnet CM remains energized, and the contacts 96 are closed by the tape 10 at the reading station 20, the cycles of operation of the apparatus will be repeated at the designed speed of the shaft 31. During each such cycle of operation, the tape will first be spaced to bring the new record field into sensing position, and such record field will then be sensed to determine the code designation therein in the manner previously described. When the field sensed bears a character code designation, a space code designation, the "Shift" code designation or the "Release" code designation, the translator relays will be operated to provide a controlling circuit path through the related solenoids to actuate the related key lever in the same manner as just explained in connection with the sensing of the 1-3-5 code designation.

As is disclosed fully in my said copending patent, when the code designation is sensed which represents a functional operation of the typewriter requiring a longer-than-normal time for its completion, provision is made for stopping the cyclic sensing operation of the reader when such

functional operations are being effected by the typewriter and for resuming the sensing operations upon a completion of such functional operation. Examples of such functional operations requiring a longer-than-normal time for their completion are carriage-return, tabulating, and back-space. From an examination of Fig. 12b, it will be noted that each of the key lever actuating solenoids 247 for effecting these three last-mentioned functional operations is connected to a circuit wire 491, and that the latter is in turn connected through a wire 492, plug socket connections T49 and R49 and the wire 490 with one input terminal of a rectifier 493. The other input terminal of the rectifier 493 is connected by the wire 409 and switch 24 with the A. C. supply wire 401. If the switch 224 is closed instead of switch 24 such other input terminal of rectifier 493 is connected to supply wire 401 through plug sockets R50 and T50, wire 405, wire 413, wire 412, switch wire 224, wire 411, plug sockets T55 and R55, and wire 410.

Thus, when the code designation corresponding to either the carriage return, tabulating or back space operation is sensed, and the translator is adjusted thereby to condition a controlling circuit through the solenoid 247 corresponding to the sensed code designation, the closing of the A. C. common contacts 108 will energize such corresponding solenoid 247 and will connect the input terminals of rectifier 493 across the A. C. supply line. One D. C. output terminal of the rectifier 493 is connected by a wire 494, relay contacts 495 and wire 496 with one side of a bucking coil 497 of relay 448, and the other side of the coil 497 is connected with the other D. C. output terminal of the rectifier. With the relay 448 energized, the contacts 495 are closed. Consequently, the just described closing of A. C. common contacts 108 will result in the energizing of bucking coil 497. The coils 497 and 450 are oppositely wound, and the coil 497 is of sufficient strength to overcome the coil 450 and cause relay 448 to drop out and thereby open its holding contacts 453. The contacts 495 also drop out and break the circuit through the bucking coil 497. The contacts 455 in the clutch magnet circuit also open to deenergize the clutch magnet CM and thereby stop further sensing operations. The pick-up contacts 447 close, but the main coil 450 cannot be energized again until other normally open contacts in the pick-up circuit are closed.

As explained in my said copending patent, the typewriter includes an element which operates when a carriage return operation is begun, to open contacts 373 and close contacts 374, and operates to reclose contacts 373 and open contacts 374 when the carriage return operation is completed. As the contacts 373 are in the clutch magnet circuit, the latter circuit will now be open at two points, viz., the contacts 373 and 455. When the contacts 374 close, they establish a pick-up circuit for the main coil 450 of relay 448 through the now closed pick-up contacts 447. This pick-up circuit is as follows: from the D. C. plus bar 416, plug sockets R54 and T54, wire 456, contacts 374, wire 469, insert switch 221, wire 445, sockets T51 and R51, wire 446, pick-up contacts 447, wire 449, main coil 450, wire 451, contacts 96, and wire 452 to the minus bus 417. The relay 448 is thereby again picked up and is held by its hold contacts 453 as before and its contacts 455 in the clutch magnet circuit close, but the latter circuit is not closed as typewriter contacts 373 are still open. When the carriage return operation is

completed and the contacts 373 again close the clutch magnet CM is energized and the cyclic sensing operations of the reader continue as before.

When the typewriter begins a tabulating operation the contacts 326 in the clutch magnet circuit are opened by an element of the typewriter and contacts 327 are closed. Thus, when the code designation representing a tabulating operation is sensed, the typewriter carriage is tabulated and the master control relay 448 is dropped out by the energizing of the bucking coil 497, and the clutch magnet circuit is opened both by contacts 326 and 455. The closing of contacts 327 connects the wires 456 and 469, the same as contacts 374, and they thereby establish the pick-up circuit which was traced above for master control relay 448. The relay 448 is held energized by its contacts 453, and when the tabulating operation is completed and the contacts 326 again closed, the clutch magnet circuit is again established and cyclic reading operations are resumed.

When a back-space code designation is sensed, the typewriter is caused to back space and the master relay 448 is dropped out due to the energizing of the bucking coil 497, and the clutch magnet circuit is opened by relay contacts 455, as before. However, as a back space operation only requires a relatively short period of time to be completed, the relay 448 is immediately picked up again and held and the clutch magnet circuit restored by the contacts 455. The latter is effected by contacts 310 connecting wires 456 and 469, such contacts 310 being closed by a typewriter element which moves as a result of a back-space operation as explained in said copending application.

The operation of the reader 100 may be manually stopped by depressing either stop switch 26 or 226. One side of switch 26 is connected directly to the A. C. supply wire 400 and the other side of switch 26 is connected to the other A. C. supply wire 401 through a wire 425, a wire 426, the rectifier 493 and wire 409 and switch 24. One side of stop switch 226 is connected to the A. C. supply wire 400 through the wires 404, 403, plug sockets T56 and R56, and wire 402, and the other side of switch 226 is connected to the other A. C. supply wire 401 through the wires 491 and 492, plug sockets T49 and R49, the wire 490, the rectifier 493 and the wire 409 and switch 24. Thus, when either switch 26 or switch 226 is depressed the rectifier 493 is connected across the A. C. supply line and the bucking coil 493 is thereby energized to drop out the master control relay 448 and thereby open the clutch magnet circuit and stop the reader. Reading operations can then be resumed only by depressing either of start switches 25 or 225 to pick up the master control relay, as previously described.

In accordance with the present invention provision is made in the apparatus disclosed for automatically stopping the operation of the apparatus in response to the producing of a significant code signal. As shown in Fig. 13, the "Stop" code designation indicated at the extreme right-hand end of the tape comprises code holes in the number 1, 4, 5, and 6 code positions. The sensing of this 1-4-5-6 code designation when the typewriter is in either case position, energizes translator magnets M1, M4, M5, and M6 and thereby establishes a circuit flow path through the translator including the transfer contacts M1-1 in their lower or transferred position, wire 479, contacts M2-2 in the position shown, wire 75

480, contacts M3-3 as shown, a wire 500, contacts M4-5 in their lower position, wire 501, contacts M5-10 in their lower position, wire 502, contacts M6-20 in their lower position, and a terminal wire 503. The wire 503 is connected by the wire 426 to one A. C. input terminal of the rectifier 493. Thus, with the closing of the A. C. common contacts 108, current flows through a circuit including the A. C. supply wire 400, the wire 477, contacts 108, wire 478, the controlling circuit flow path just described as being established by the sensing of the 1-4-5-6 code code designation, the rectifier 493, and wire 409, switch 24, and the other A. C. supply wire 401. It will be apparent that if the switch 224 is closed instead of the switch 24, the circuit will include instead of wire 409 and switch 24, the plug sockets R50 and T50, wires 405, 413 and 412, the switch 224, wire 411, plug sockets T55 and R55, and wire 410. The flow of current through this circuit closed by contacts 108 therefore energizes the bucking coil 497 and drops out master control relay 448, thereby opening relay contacts 455 and the clutch magnet circuit which deenergizes the clutch magnet CM and stops further reading operations, as explained hereinabove.

As explained herein at the beginning of this specification, it is also a feature of the present invention to provide for automatically stopping the reader in response to the sensing of a significant code designation with the type basket in shifted case position, and to provide for the printing of a normal case letter character when this same significant code designation is sensed with the type basket in its normal case position. As shown in Fig. 13 the 3-5 code designation represents the normal case letter character "H." There is no shifted case character represented by the 3-5 code designation. When the 3-5 code designation is sensed, translator magnets M3 and M5 are energized and a controlling circuit flow path is thereby established through the translator which path is connected to the terminal circuit wire 506 and plug socket connections R8 and T8. This circuit flow path through the translator will not be traced as it is believed that it will be obvious from the foregoing description. As shown in Fig. 12b, plug socket T8 is connected by a wire 507 with the center blade or strap 206 of the transfer contacts 201, the lower strap 204 is connected by a wire 508 with the solenoid 247 for actuating the "H" type bar, and the upper strap 202 is connected by a wire 509 with the wire 491 and through the wire 492, plug sockets T49, R49, wire 490, rectifier 493, wire 409 and switch 24 with the A. C. supply wire 401. If the switch 224 is closed instead of switch 24, the connection to wire 401 through the switch 224 will be the same as that traced above in connection with the stop code 1-4-5-6. As explained hereinabove, the transfer contacts 201 are held by the arm 208 in the position shown in Fig. 12b when the type basket is in its normal case position. Thus, with the type basket in normal case position and upon the sensing of the 3-5 code designation and the closing of A. C. common contacts 108, A. C. current will flow through the last mentioned circuit flow path established by the translator, and through plug sockets R8 and T8, the wire 507, transfer contacts 201 in the position shown, the wire 508, and the solenoid 247 for the letter "H." This will result in the printing of the letter "H" in the manner previously explained.

As explained above, when the "Shift" code

designation is sensed, the type basket is adjusted to its shifted case position and the transfer contacts 204 are adjusted so that points 203 and 207 close and points 205 and 207 open. It will, therefore, be apparent that with the type basket in its shifted position and upon sensing the 3-5 code designation, the closing of the A. C. common contacts 108 will provide for the flow of A. C. current through the circuit flow path established by the translator and the plug sockets R8 and T8 as before, and also through the wire 507, contact points 207 and 203, wire 509, wire 491, wire 492, plug sockets T49 and R49, the wire 490 and through the rectifier 493, the wire 409 and switch 24. As will be obvious from the previous description, the closing of this latter A. C. circuit will drop out the master control relay 448, thereby opening contacts 455 and the clutch magnet circuit and stopping further sensing operations by the reader.

While there have been shown and described and pointed out the fundamental novel features of the invention as applied to a preferred embodiment, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. In apparatus for printing character data on a copy sheet in accordance with data-representing designations recorded in a record sheet, the combination of means for sensing successively said data designations; translator means providing circuit flow paths corresponding, respectively, to the designations sensed; a typewriter including a platen, a plurality of selectively actuatable type members cooperating with said platen to print character data on said copy sheet, case shifting mechanism adjustable to occupy a normal case position and a shifted case position, and a plurality of actuators for effecting, respectively, the actuation of said type members and the functional operations of the typewriter including the adjusting of said mechanism to its said shifted case position and the return of said mechanism to its said normal case position, said actuators being rendered effective, respectively, by the establishing of corresponding circuit flow paths by said translator means; means for controlling the operation of said sensing means and comprising a master control relay having a pair of contacts and including a main coil effective when energized to adjust said contacts to start and maintain operation of said sensing means and a bucking coil effective when energized to adjust said contacts to stop operation of said sensing means; adjustable contact means operated by said case shifting mechanism, and effective, when the latter occupies its said normal case position, and when a circuit flow path is established through the translator means which corresponds to a predetermined one of said type-member actuators, to provide for the actuation of said one actuator and thereby printing the normal case character of the related type member, and effective when said shifting mechanism occupies its said shifted case position and upon the establishing of said last-named circuit flow path, to provide for energizing said bucking coil.

2. In data printing apparatus, the combination

of signal producing means operable to successively produce signals representing character data according to a predetermined code system; translating means responsive to the signal producing means and operable to establish circuit flow paths corresponding, respectively, to the character signals produced; printing means comprising means for holding a copy sheet in printing position, a plurality of type members operable, when actuated, to print corresponding characters on a copy sheet, a plurality of electrically responsive character actuators adapted to be energized by the establishing of corresponding circuit flow paths by said translating means and effective when so energized to actuate corresponding type members, and case shifting mechanism operable to adjust said printing means to first and second case positions; control means adjustable to operative and to non-operative conditions and effective when in its operative condition to effect continuing operation of said signal producing means and effective when in its non-operative condition to stop operation of said signal producing means; an electrically responsive control device operable when energized to adjust the control means to its non-operative condition; and selective contact means adjustable in response to said case shifting mechanism and effective when the latter occupies said first case position to electrically connect one of said circuit flow paths which corresponds to a predetermined character signal to its corresponding character actuator for energizing the latter and said contact means being effective when said case shifting mechanism occupies said second case position to electrically connect said one circuit flow path to said control device for energizing the latter.

3. In data printing apparatus, the combination of means for producing signals representing both character data and functional operations in accordance with a predetermined code system; translating means responsive to said signal producing means and operable to establish circuit flow paths corresponding, respectively, to the character and functional representing signals produced by said signal producing means; printing mechanism including means for holding a copy sheet in printing position, a plurality of selectively-actuatable character type members cooperating with said platen to print corresponding character data on the copy sheet, case shifting mechanism selectively adjustable to occupy first and second case positions, a plurality of electrically responsive character actuators energized, respectively, by the establishing of corresponding circuit flow paths by said translating means and said actuators being operable when so energized to actuate type members corresponding to the signals produced, and electrically responsive functional actuators operable to adjust said case shifting mechanism to its said first and second case positions in response to the producing of significant functional representing signals and the establishing of corresponding circuit flow paths; control means adjustable to an operative and a non-operative condition and effective when in its operative condition to maintain operation of said signal producing means and effective when in its non-operative condition to stop operation of said signal producing means; an electrically responsive device effective when energized to adjust said control means to its said non-operative condition; and selective contact means adjustable in response to said case shifting mechanism and effective when the latter occupies its said first

case position and upon the producing of a predetermined character representing signal, to electrically connect its corresponding circuit flow path to the type member actuator corresponding thereto for energizing the latter and said contact means being effective when said shifting mechanism occupies its said second case position and upon the producing of the same predetermined character signal, to electrically connect said corresponding circuit flow path to said electrically responsive device for energizing the latter.
